[57] CLAIM

The ornamental design for multi-media organizer case, as shown and described.

DESCRIPTION

FIG. 1 is a view showing the front design of the opened up multi-media organizer case;

FIG. 2 is a rear view of the FIG. 1 multimedia organizer case;

FIG. 3 is a left side view of the multi-media organizer case as shown in FIG. 1, the right side being the same;

FIG. 4 is a top view of the FIG. 1 multi-media organizer case;

FIG. 5 is a bottom view of the FIG. 1 multi-media organizer case;

FIG. 6 is a perspective view showing the multi-media organizer case folded up;

FIG. 7 is a view like FIG. 1, showing the interior of the multi-media organizer case case after a flap has been folded to the left; and,

FIG. 8 is a perspective view showing the multi-media organizer interior, with the flap only partly folded.
